Charles Turner Brown
ATTORNEY.

UNITED STATES PATENT OFFICE.

STEWART BROWN, OF CHICAGO, ILLINOIS.

WIND-SHIELD FRAME.

1,022,719.

Specification of Letters Patent.

Patented Apr. 9, 1912.

Application filed November 6, 1911 Serial No. 658,779.

To all whom it may concern:

Be it known that I, STEWART BROWN, a citizen of the United States, residing at Chicago, in the county of Cook and State 5 of Illinois, have invented certain new and useful Improvements in Wind-Shield Frames, of which the following is a specification.

This invention relates to frames for wind shields which comprise one or more plates 10 of glass inclosed in a frame and mounted in front of the driver's seat of automobiles or other vehicles.

To those familiar with the art it is known 15 that in heavy automobiles, particularly those which are provided with a limousine body the glass of the wind shield is frequently broken by the swaying of the said body.

The object of this invention is to obtain 20 a wind shield frame of pleasing appearance in which glass will not be broken, which is simple in construction, easily made and not liable to get out of order.

In the drawing Figure 1 is a front elevation 25 of a device embodying the invention. Fig. 2 is a vertical section on line 2—2 of Fig. 1, viewed in the direction indicated by the arrows. Fig. 3 is a vertical section, on an enlarged scale, of a short section of the 30 frame, showing the construction used for mounting spiral springs forming elements in the device. Fig. 4 is a front elevation of a modification of the device.

Similar letters refer to similar parts 35 throughout the several views.

A, A, are the top and bottom pieces and a, a, are the side pieces of the outer and flexible frame of the device.

B are corner pieces which are made of 40 resilient metal, as hard brass, which are attached to adjacent ends of the pieces A, a, by bolts, rivets or screws b, to obtain the corners of the outer frame. The fastenings b are positioned some way back of the ends 45 of the parts A, a, so as to obtain the required resiliency to the corner pieces B.

The pieces A, a, are respectively made 50 with three sides or U-shaped and C is a frame consisting of top, bottom and side pieces which are rigidly secured together at their ends, which fits into the open sides of the top, bottom and side pieces of the outer frame, and which rests on the lugs or abutment D, D, within bottom pieces A of the 55 outer frame.

E are springs which yieldingly hold the

inner frame in determined relative position to the sides of the outer frame and E' are springs which yieldingly hold the inner frame down on the lugs or abutments D.

F are thimbles secured in one of the walls of frame C. Springs E extend through said thimbles F.

G, G', are frames in which the plates of glass H, H', are respectively secured.

I, I, are hinges by means of which the frame G' is attached to the top bar of frame C.

In the modification illustrated in Fig. 4 the outer frame is constructed as hereinbefore described, and comprises the top and bottom bars A, side bars a, corner pieces B and bolts or rivets b, and said modification comprises also the inner frame C, frames G, G', and plates or sheets of glass H, H'. In the modification the lugs D and springs E are omitted and in place thereof the frame C is suspended in the outer frame on pins J, J. Substantially the same movement of the frame C relative to the outer frame is 70 permitted in this modification that obtains in the construction illustrated in Figs. 1, 2 and 3.

The swaying of the wind shield which in this construction is limited to the outer 85 frame in one direction is indicated by the broken line K in Fig. 1 and the swaying in the other direction is indicated by K' in Fig. 4. The swaying of the outer frame is permitted by the resilient corners B and the only effect of said swaying on the rigid frame C is to slightly change the relation of said frame C to said outer frame and this change of relative position of the two frames is permitted in the construction illustrated in Figs. 1, 2 and 3 by the spring E, the said inner frame sliding on the lugs D and said movement is permitted in the construction illustrated in Fig. 4 by the hanging of the inner frame C on pins J in such manner that 90 the outer walls C' of the frame C are some distance away from the inner face of the corresponding walls (lettered a' in Fig. 3), of sides a.

The top and bottom A and the sides a of the outer frame may be made of U-shaped metal bars or of U-shaped wooden bars, but I have so far made them of metal.

I claim:

1. A wind shield frame comprising an 110 outer frame, having top, bottom and side pieces joined together by resilient corner

pieces, in combination with a rigid frame contained within the outer frame and yieldingly joined thereto.

2. A wind shield frame comprising an outer frame having top, bottom and side pieces which are respectively U-shaped in cross section and joined together by resilient corner pieces, in combination with a rigid frame fitting between the sides of the pieces forming said top, bottom and sides of the outer frame, and means to yieldingly hold said inner frame in determined relation to the outer frame.

3. A wind shield frame comprising an outer frame having top, bottom and side pieces which are respectively U-shaped in cross section and joined together by resilient corner pieces, in combination with a rigid frame fitting between the sides of the pieces forming said top, bottom and sides of the outer frame, and springs between the inner

and outer frames, to yieldingly hold said inner frame in determined relation to the outer frame.

4. A wind shield frame comprising an outer frame having top, bottom and side pieces which are respectively U-shaped in cross section and joined together by resilient corner pieces and lugs contained on the inner surface of said bottom piece, in combination with a rigid frame fitting between the sides of the pieces forming said top, bottom and sides of the outer frame, and resting on said lugs, and springs between the inner and outer frames, to yieldingly hold said inner frame in determined relation to the outer frame.

STEWART BROWN.

In the presence of—

CHARLES TURNER BROWN,
C. A. ADAMS.
